UNITED STATES PATENT OFFICE.

WILLIAM LOUDEN, OF FAIRFIELD, IOWA, ASSIGNOR TO THE LOUDEN MACHINERY COMPANY, OF FAIRFIELD, IOWA, A CORPORATION OF IOWA.

FASTENER FOR CLOSURES.

1,385,563.

Specification of Letters Patent.

Patented July 26, 1921.

Application filed June 18, 1920. Serial No. 389,871.

To all whom it may concern:

Be it known that I, WILLIAM LOUDEN, a citizen of the United States, residing at Fairfield, in the county of Jefferson and 5 State of Iowa, have invented a new and useful Improvement in Fasteners for Closures, of which the following is a specification.

My invention relates to closures which may be readily placed in an animal pen or 10 in other structures to make a partition in the structure, or for other purposes, and which may be readily opened when occasion requires, and it consists of a combination and arrangement of certain attachments applied to the closure hereinafter described and specifically set forth in the claims.

In the accompanying drawings forming part of this specification, Figure 1 is a side elevation of a panel hinged to a top rail connected to the sides of a pen, so as to form 20 a partition in the pen and showing the invention applied to an animal pen. Fig. 2 is a similar view of a panel set in between the sides of a pen and held in that position by readily releasable means so as to form a 25 partition in the pen and to be bodily removed therefrom. Fig. 3 is an enlarged side elevation of one of the fastening devices. Figs. 4 and 5 are transverse sections 30 on lines 4—4 and 5—5 of Fig. 3. Fig. 6 is an enlarged detail view. Fig. 7 is a perspective of a central portion of an animal pen, showing the panel of Fig. 1 swung up to the top of the pen and being held in said 35 position by the fasteners contacting with the top-rail of the pen.

Referring to Fig. 1 of the drawings, A represents posts on opposite sides of a central portion of a pen, B a transverse section 40 of a top-rail connected to each post, and C a rail extending across and having its ends connected to the top-rails B. The figure also shows a panel comprising top and bottom rails, D and D', side-rails E and a 45 number of fillers F, the fillers in the sides of the pen in Fig. 7 being represented by F. The top-rail D of the panel is connected to the cross-rail C by means of hinge members G so that when released from connection 50 with the sides of the pen it may be swung up level with the top-rails B, and be held in that position so as to virtually remove the partition and throw both sections of the pen into one as shown by Fig. 7.

55 To hold the panel in position, either

closed or open, I use fasteners H which are pivoted to the side rails E and are adapted to engage the posts A and to be disengaged therefrom. These fasteners are composed of two sets of members h, each having their 60 ends set at substantially right angles, and spaced a sufficient distance apart to embrace the posts A and side-rails E. The members h are joined together by brackets h' bolted or riveted together, as most plainly shown in 65 Fig. 5. These fasteners are placed astraddle of the side rails of the panel and are pivoted thereto at I so that while one of their ends will straddle the side rail E, the others will straddle the posts A.

To hold the fasteners in this position, I place links or elongated rings J, (shown in Fig. 6), on the side-rails E above the fasteners and slip them down over the ends astraddle of said rails. When this is done 70 the panel will be held in place by the ends of the members h straddling the posts A. To release the panel all that is necessary is to slip the ring J up above the ends of the members which straddle the side-rails E, so 75 the fasteners may be rotated on their pivots and the ends straddling the posts A may be raised sufficiently to release the posts and permit the panel to be swung on its hinges.

When this is done the panel may be swung 80 up level with the top-rails B and the adjacent ends of the locking devices may be placed astraddle of said top-rail as shown in Fig. 7, and by slipping the rings J over the adjacent ends of the fasteners, the panel 85 will be held stationary in this horizontal position and level with the top-rail B. In this way small animals, such as hogs and sheep will be free to pass under the panel from one end of the pen to the other.

To permit larger animals to pass freely from one end of the pen to the other without making the pen higher than necessary, it is 90 advisable that arrangements be made to bodily remove the partition. To accomplish 95 this result, I remove the cross-rail C and hinges G and preferably make the panel the same height as the sides of the pen, extending the side-rails E' down so they will rest on the floor of the pen, as shown in Fig. 2. 100 When arranged in this way, it is necessary to use two sets of fasteners H, a set on each side applied to the side-rails E' near their upper and lower ends. When the fasteners are turned so their ends will straddle the 105 110

posts A and are held in this position by the rings J, the panel will be held rigidly in engagement with the sides of the pen.

To remove the panel, all that is necessary is to slide up the rings J and then turn the fasteners on their pivots so their ends will be free of the posts A, or the other portions of the sides of the pen to which they may be connected. The lower locking device H' at the right hand side of Fig. 2 is shown in this position and it also shows the ring J used to hold the locking device in open position. When all the locking devices are in this position the panel may be removed to change the pen from two compartments into a single compartment. No tools are required except perhaps a hammer or a small bar to drive the rings upward or downward to release or to hold the locking devices in position on the side-rails E or E'.

In the drawings, inwardly turned points K are shown on the ends of the fasteners which are designed to straddle and be held by the rings J on the side-rails E and E', when the fasteners H are in locked position. The object of these inwardly turned points is to prevent the ends on which they are placed from passing beyond the rails E or E'. In place of these points the brackets h' which are riveted or bolted together might be used to secure the same result, but if the nearest filler should be set quite close to the side-rail E or E' the ends h' might project out so far that they would come in contact with the nearest fillers, and in this event the fasteners H might be prevented from turning sufficiently on their pivots to become disengaged from the posts A.

Also, sometimes a sheet-iron filler is used instead of the pipe fillers shown in the drawing, and frequently the adjacent edges of this sheet-iron filler are set quite close to the side-rails E or E', and in such construction the brackets h' could not be used on that side of the fastener because they would come in contact with the edges of the sheet-iron filler. The inwardly projecting points K will prevent the ends of the fasteners from passing beyond the side-rails, and they will not interfere with fillers which are materially thinner than the side-rails.

L represents the floor of the pen and M the curbs in which the posts A are set. In the form shown by Fig. 2 the lifting of the panel may be prevented by drilling holes N in the side-rail above the upper holding devices and inserting pins in these holes, if under any circumstances this should be deemed advisable. The rings J being placed on the side-rail cannot be lost or misplaced. The device is exceedingly simple and effective in operation. These fasteners may be used in various ways, either in pairs, as shown by the drawing, or singly when the opposite side of the closure is otherwise se-

cured, as will be readily understood by those skilled in the art. These fasteners are extremely simple and inexpensive, and are effective and easily operated.

What I claim is:

1. In fasteners for closures a pair of members spaced in parallel relation a distance apart, the ends of each member being disposed at substantially right angles to each other, in combination with a closure having a side rail straddled by the members and upon which they are pivoted at a point centrally between their outstanding ends, and a fixed rail adjacent thereto and parallel with the side rail, whereby, as the fastener is turned on its pivot, one set of its outstanding ends will be adapted to straddle said adjacent fixed rail, while the other set will be held astraddle of the side rail of the closure to which it is pivoted, and the closure will be held in fixed position until the members of the fastener are turned on their pivot to release their ends from the fixed rail.

2. In fasteners for closures, the combination of two or more fasteners, each comprising a pair of members spaced in parallel relation a distance apart, the ends of each member being disposed at substantially right angles to each other, a closure having rails on opposite sides, each of which are straddled by one or more of the fasteners, and to which side rails the fasteners are pivoted at points centrally between the outstanding ends of the spaced apart members comprising the fasteners, and fixed rails adjacent and parallel with the side rails and which the ends of the fasteners are also adapted to straddle, whereby the closure will be alternately held in fixed position and be released therefrom by turning the fasteners on their pivots.

3. In a device of the character described, a pair of members, spaced substantially in parallel relation a distance apart, and having their opposite ends disposed at substantially right angles to each other, a closure having a side rail straddled by the members and upon which they are pivoted at a point centrally between their outstanding ends, a fixed rail adjacent to and parallel with the side rail of the closure, one set of the outstanding ends of the members being adapted to straddle the fixed rail and hold the closure in fixed relation and to be disengaged therefrom to release the closure, and a bracket on each of the members joined together at their outer ends, and assisting in holding the members in parallel relation.

4. In a device of the character described, a pair of members, spaced substantially in parallel relation a distance apart, and having their opposite ends disposed at substantially right angles to each other, a closure having a side rail straddled by the members and upon which they are pivoted at a point

centrally between their outstanding ends, a fixed rail adjacent to and parallel with the side rail of the closure, one set of the outstanding ends of the members being adapted 5 to straddle the fixed rail and hold the closure in fixed relation and to be disengaged therefrom to release the closure, a bracket on one end of each of the members joined together at their outer ends and assisting in holding 10 the members in parallel relation, and inwardly projecting points on the other ends of the members preventing the ends of the members to which they are affixed from passing by the side rail to which they are 15 pivoted, but permitting their passage over narrower structures.

5. In a device of the character described, a pair of members spaced substantially in parallel relation a distance apart, and hav-

ing their opposite ends disposed at substantially right angles to each other, a closure having a side rail straddled by the members and upon which they are pivoted at a point centrally between their outstanding ends, a fixed rail adjacent to and parallel with the side rail of the closure, one set of the outstanding ends of the members being adapted to straddle the fixed rail and hold the closure in fixed relation and to be disengaged therefrom to release the closure, and a slip-ring 25 on the side rail above the pivoted members adapted to pass over the parallel ends of the members and hold them in fixed position while the other ends of the members are in engagement with the fixed rail.

Fairfield, Iowa, June 16, 1920.

WILLIAM LOUDEN.
